SIMPLITRON MAGNETRON

Charles V. Litton, Redwood City, Calif.

Application October 21, 1949, Serial No. 122,634

6 Claims. (Cl. 315—40)

1

This invention relates to magnetrons, and more especially to magnetrons for operation at very high frequencies.

A principal object is to provide a magnetron assembly which is capable of efficient operation at frequencies of the order of 8 to 50 centimeters wavelength.

I have disclosed in my prior application Serial No. 694,259, filed August 31, 1946, now Patent No. 2,551,614, granted May 8, 1951, a novel and simplified construction of magnetrons employing a single vane which cooperates with a magnetron anode-cavity to produce very high frequency oscillations. The present invention is in the nature of an improvement on the electrode arrangement and mounting of that type of magnetron device.

A feature of the invention relates to an improved electrode mount for very high frequency magnetrons, whereby the utmost dimensional accuracy can be achieved with the desired operational stability of the magnetron and without correspondingly increasing the cost of manufacture and assembly.

Another feature relates to a novel construction of filament end cap shielding arrangement for magnetrons of the single magnetron cavity type.

A further feature relates to a simplified magnetron tube for use at very high frequencies, wherein the parts are designed to facilitate accurate assembly and alignment by conventional assembling techniques.

The above-mentioned and other features and objects of this invention, and the manner of attaining them, will become more apparent, and the invention will be best understood, by reference to the following description of an embodiment of the invention taken in conjunction with the accompanying drawings, wherein:

Fig. 1 is an isometric perspective view, partly sectional, illustrating the electrode arrangement.

Fig. 2 is a longitudinal sectional view of Fig. 1.

Fig. 3 is a sectional view of Fig. 2 taken along the line 3—3 thereof.

Fig. 4 is a sectional view of Fig. 2 taken along the line 4—4 thereof.

Fig. 5 is a sectional view of Fig. 1 taken in a plane at right angles to the sectional plane on which Fig. 2 is taken.

Fig. 6 is a schematic wiring diagram of the circuits for energizing the magnetron of Figs. 1 to 5.

Referring to Figs. 1 to 5, the magnetron comprises a glass stem or header 1 of any well-known form, and it may comprise a reentrant neck 2 terminating in a cruciform press 3. A suitable

2

exhaust tubulation 4 is provided for evacuating the completed tube. Sealed in a vacuum-tight manner through the press 3 are two lead-in wires or rods 5, 6, which conduct the heating current to the filamentary cathode 7. This cathode may be in the form of a convoluted or helical wire carrying the usual coating of electron-emissive material, such as is well known in electron discharge devices generally.

10 Also sealed into the press, preferably in a plane perpendicular to the plane of rods 5, 6, are two metal rods 8, 9, which are tightly fitted and suitably anchored into one end of a metal anode block 10. As shown more clearly in Fig. 4, the block 10 is circular in cross-section except for the recesses 11, 12, on opposite sides. These recesses are sufficiently large in cross-section to allow the filament rods 5, 6, to pass freely therethrough without any danger of short-circuiting to the anode.

15 The end of block 10 remote from the press is formed with a central rectangular projection 13 which has its forward end undercut to form a cylindrical recess or cavity 14. This cavity 14 has a window 15, and preferably the edges 16, 17, thereof are chamfered.

20 Sealed or otherwise fastened to each of the rods 5, 6 are metal buttons or caps 18, 19, each cap having a central recess into which the respective opposite ends of the coiled filamentary cathode 7 are fitted. The ends of this filamentary cathode are preferably welded to the caps 18 and 19. These caps have a diameter which is greater than the diameter of the circular cavity 14, and they are preferably provided with reduced shoulders 20 which are located in close proximity to, but spaced from, the ends of cavity 14. Thus the ends of the said cavity are substantially entirely protected against the emergence of electrons from the opposite ends thereof. The foregoing elements form a structural unit.

25 In order to complete the enclosing envelope, there is provided another structural unit, consisting of the tubular glass member 21 which is sealed at 22 to the stem 1. The opposite end of member 21 has sealed in a vacuum-tight manner thereto, a tubular metal member 23 with the opposite ends provided with feathered edges 24, 25. The edge 24 is sealed in the well-known manner into the body of the glass member 21. The end 25 has sealed thereto a glass button 26 which also has sealed centrally therethrough a metal rod 27 preferably, although not necessarily, of tungsten. The member 23 has a shoulder portion 28 which is adapted to seat against a cor-

responding shoulder 29 on the anode block 10. The member 23 can be made of copper, or other similar metal or alloy which can be sealed in a vacuum-tight manner to the glass members 21 and 26. In order to facilitate assembly of the parts, the reduced portion 30 of member 23 can be provided with a longitudinal inwardly-formed bead 31 which is arranged to register with a corresponding longitudinal recess or groove 32 in the wall of anode block 10. Thus by reason of the cooperating shoulders 28, 29, and the cooperating rib 31 and groove 32, the parts can be readily assembled with the desired degree of accuracy.

As shown in Figs. 1, 2 and 5, the end of rod 27 adjacent cavity 14 is provided with a taper 33. Preferably the parts are so dimensionally related that the distance between the extreme end 34 of rod 27 and the opposite wall of cavity 14 is approximately equal to the cavity diameter, and the spacing between the edge 33 and the cavity edges 16 and 17 of the cavity window are correlated with the frequency for which the magnetron is designed to be used. In the well-known manner, a suitable magnet having the respective north and south pole pieces 35, 36 is mounted with respect to the cathode 7, so as to cause the emitted electrons to travel in the proper trajectories around the longitudinal axis of the cathode, and so that these trajectories intercept the cavity edges 16, 17, and the edge 34 in the proper phase relation to generate oscillations. It will be understood, of course, that a suitable direct current potential is applied to the anode 12 and to the rod 27, which potential is relatively high compared to the cathode potential. If desired, the magnet is mounted in an adjustable cradle so that its orientation around the member 30 can be adjusted to achieve the proper electron trajectories. Arranged to be telescoped over the end of member 33 is the outer tubular conductor 37 of a coaxial wave transmission line whose center conductor is also arranged to be connected to the rod 27. An adjustable plunger 38 which operates as a combination tuner and output transformer is mounted within the conductor 37. The member 33 and the portion 37 of the coaxial line form, together with the end of member 30, a cavity resonator which can be tuned by adjustment of the plunger 38. The plunger 38 provides a short between conductors 27 and 37, the plunger 38 being shaped to provide an abrupt discontinuity on the tube side and a tapered transformer on the load side. The abrupt end of the plunger is provided with a slideable contact 38a in engagement with conductor 37 and a grounding coil 38b in engagement with conductor 27. This exponential transformer is broad band and provides uniform loading over the useful band.

It will be understood, of course, that any other well-known manner of tuning the cavity can be provided. For example, the insulator member 28 carrying the rod 27 can be sealed to the end of member 30 by a metal bellows or sylphon whose effective length can be adjusted. Likewise, if desired, the rod 27 can be sealed to the member 26 by a separate metal bellows or sylphon so as to adjust the spacing between the edge 34 and the magnetron cavity 14.

Fig. 6 shows, in schematic form, the various elements of the magnetron, together with the appropriate potential supplies therefor. Thus the filamentary cathode 6 is provided with a suitable heating supply current source 39, and a

suitably high direct current potential source 40 has its negative end connected to the cathode 6 and its positive end connected through a suitable high frequency choke coil 41 to the anode 10 and to the electrode 27. If desired, the anode 10 and electrode 27 may be connected to separate and adjustable direct current supplies so as to vary the relative direct current potentials for the required frequency of oscillation from the magnetron.

While I have described above the principles of my invention in connection with specific apparatus, it is to be clearly understood that this description is made only by way of example and not as a limitation to the scope of my invention.

What is claimed is:

1. A magnetron, comprising a tubular metal member having means closing off each end in a vacuum-tight manner, a metal anode block telescopically fitted into said tubular metal member, said block having means defining a single cavity therein with one wall of the cavity having a magnetron gap, another anode having an edge in spaced registry with said gap, and an electron-emitting cathode centrally mounted within said cavity.
2. A magnetron, comprising an evacuated envelope constituted in part of a tubular metal member, a metal anode block telescoped into said tubular member, said block having one end provided with a magnetron cavity therein having a single magnetron gap which in plan cross-section is substantially the shape of a circle, an electron-emitting cathode centrally mounted within said cavity, magnetic means disposed at opposite ends of said cavity for causing the electrons to precess around said cavity and past said gap, and another anode having a substantially linear edge in registry with said gap and symmetrically spaced from the edges of the gap and said edge being located substantially on said circle.
3. A magnetron, comprising an evacuated envelope constituted in part of a tubular metal member, a metal block telescoped into said tubular member, said block having one end provided with a magnetron cavity therein having a single magnetron gap, an electron emitting cathode centrally mounted within said cavity, magnetic means disposed at opposite ends of said cavity to cause the electrons to precess around said cavity and past said gap, and another electrode having a substantially linear edge in registry with said gap and symmetrically spaced from the edges of said gap, said block being substantially circular in cross-section and provided at said one end with an integral and substantially rectangular projection in which said magnetron cavity is formed.
4. A magnetron, comprising an evacuated envelope having a header at one end, a plurality of lead-in conductors sealed in a vacuum-tight manner through said header, a tubular metal member forming part of the wall of said envelope, an anode block supported from one of said lead-in members and telescoped within said tubular metal member, said block having means defining a transverse magnetron cavity, said cavity having a single gap, an electron emitting cathode located within said cavity, means including a pair of said lead-in conductors supporting said cathode at its opposite ends, and another anode having an edge in registry with said cavity and symmetrically spaced from the edges of said gap.

5. A magnetron, comprising an evacuated envelope consisting of a glass header, a tubular metal member sealed to said glass header, said tubular metal member having a peripheral shoulder, a lead-in conductor sealed through said header, an anode block attached to the inner end of said conductor, said anode block having a shoulder in abutment with the shoulder on said tubular metal member, a cooperating rib and recess on said tubular metal member and said block for preserving a predetermined orientation of the block with respect to the tubular metal member during the assembly thereof, said tubular metal member overhanging the end of said block, an insulator member sealing-off the open end of said tubular metal member, means in said block defining a substantially cylindrical magnetron cavity with a single magnetron gap, an electron-emitting cathode symmetrically located within said magnetron cavity, a plurality of lead-in members sealed through said header and passing along said block supporting said cathode at opposite ends, and another electrode passing through said insulator sealing member and having an edge in registry with said magnetron gap to bisect said gap.

6. A magnetron tube having an evacuated envelope comprised of a glass stem with a plurality of lead-in conductors sealed therethrough, a tubular metal member forming part of said envelope and sealed at one end to said stem, an insulator button sealing the opposite end of said tubular member, said tubular member hav-

ing a peripheral shoulder and a longitudinally extending rib, a metal anode block fitted within said tubular member and having a peripheral shoulder and a longitudinally extending groove for respective registry with the shoulder and rib on said tubular member, said block having a pair of oppositely disposed longitudinally extending grooves through which freely pass a pair of said lead-in conductors, said block having a magnetron cavity with a single magnetron gap located adjacent the ends of said pair of conductors, electron shielding caps attached to the said ends of said pair of conductors, an electron-emitting cathode connected at its opposite ends to said caps and passing through said magnetron cavity, and another electrode sealed through said insulator button and extending with its edge adjacent said magnetron gap.
